STAMPING DIE HOLDER

Leon C. Hauer, Ross Township, Pittsburgh, Pa., assignor to M. E. Cunningham Company, Pittsburgh, Pa., a corporation of Pennsylvania

Application February 24, 1951, Serial No. 212,601

5 Claims. (Cl. 101—28)

1

This invention relates to a holder for dies and the like and is an improvement of the device disclosed in my pending patent application for a Stamping Die Holder, U. S. Serial No. 749,439 filed May 21, 1947 now Patent No. 2,601,824.

The principal object of this invention is to provide an improved die holder in which one or more dies may be yieldably secured in the stamping position, being of sturdy and rugged construction so that it will withstand, without undue wear and injury, the intensive hammering action to which dies of this nature may be subjected. In addition to this object, the various other novel features and advantages of this invention will become apparent when the following detailed description is read in conjunction with the accompanying drawings of which:

Figure 1 is a side elevation of a stamping die holder embodying the features of the invention herein disclosed;

Figure 2 is a partial plan view of the holder shown in Figure 1;

Figure 3 is a sectional view taken on line III—III of Figure 1, and

Figure 4 is a sectional view taken on line IV—IV of Figure 1.

With reference to the drawings, the die holder 10 consists of a head or die receiving body portion 11, having a handle or grip 12 detachably secured thereto, which is adapted to yieldably receive and secure in the stamping position a plurality of dies 13. Within the head and passing therethrough there is a plurality of openings or passages 14 into which the dies are inserted and which have substantially the same shape as that of the cross-sectional area of the dies.

In order that the dies may be readily inserted within as well as withdrawn from the holder for interchange or replacement, for each die opening 14 there is provided a spring 15 which yieldably secures the dies inserted therein. The springs 15, made preferably of steel or the like having the necessary resilience and strength, are formed by bending the metallic strips back upon themselves so that one of the legs 15a thereof is somewhat longer than the other which is designated by the numeral 15b.

Adjacent to each of the openings 14 there is a passage 16 extending through the side wall of the head 11 and communicating with the opening 14, within each of which a spring is confined and retained by a cover plate 17 removably secured to the side of the head 12 by suitable screws 18, and by two wear-resistant strips 19 and 21 secured within the head, respectively at 55

2

the top and bottom of the passages 16. In addition to assisting in confining the springs within the passages, the plates 19 and 21 also serve the purpose of preventing undue wear by the relatively hard metal dies of the tool holder softer body metal particularly adjacent to the edges of the chambers within which the springs are confined.

To the top portion of the body portion 11 there is affixed a relatively hard metal cover or shock resistant plate 22 having apertures 23 therein which coincide with the openings 14 of the holder. Along the lateral edges of this plate 22, it has side walls disposed at right angles to its upper surface which have a downwardly enlarging taper for locking it into the body portion 11 when the body portion is cast. As the main body of the holder is cast of a relatively soft low melting point metal, the cover plate 22 serves as a protective covering therefor from injury which may otherwise be sustained should the operator inadvertently strike the holder with a direct or a glancing blow of the hammer. As noted in Figure 3, the spring at its bend portion bears against the wear-resistant plate 19, the shorter or free end 15b thereof extends beyond the plate 21 for engaging with and yieldably retaining a die within the holder, and the longer spring portion 15a engages the cover plate 17.

To each of the bottom corners of the die receiving portion 12 there is secured a spacer bolt 24 or the like which maintains the body portion 24 a distance above the workpiece to be operated upon and thus provides a space for viewing the lower portion of the dies in order to assist the operator in placing the dies in the desired position.

In accordance with the provisions of the patent statutes, I have explained the principle and operation of my invention and have illustrated and described what I consider to represent the best embodiment thereof. However, I desire to have it understood that within the scope of the appended claims the invention may be practiced otherwise than as specifically illustrated and described.

I claim:

1. A tool-holder within which a stamping die or the like is adapted to be yieldably secured in the stamping position comprising a grip, a body portion having an opening therethrough adapted to receive a die the cross section of which conforms substantially to the shape of said opening, a yieldable member for engaging with and retaining a die inserted within said opening, a protec-

3

tive cover plate secured to the top of the body portion and surrounding said opening on the side from which a die is normally inserted and having downwardly enlarging side walls along its lateral edges locking it into engagement with said body portion, and a wear resistant strip secured within the body portion adjacent said yieldable member forming a protective surface against which a die may make slidable contact.

2. A tool-holder within which a stamping die or the like is adapted to be slidably secured in the stamping position comprising a grip, a body portion having an opening therethrough adapted to receive a die the cross-section of which conforms substantially to the shape of said opening, a yieldable member for engaging with and retaining a die within said opening, a detachable side wall forming a closure for said yieldable means, a protective cover plate secured to the body portion at the side thereof from which a die is normally inserted and having an opening therethrough coinciding substantially with the die receiving opening, and wear-resistant strips, secured within said body portion on either side of and engaged by a portion of said yieldable means, forming a protective surface against which a die may make slidable contact.

3. A tool-holder within which a stamping die or the like is adapted to be yieldably secured in the stamping position comprising a grip, a body portion having an opening therethrough adapted to receive a die the cross-section of which conforms substantially to the shape of said opening, a spring for engaging with and retaining a die inserted within said opening, a protective cover plate secured to the body portion on the side from which a die is normally inserted and having an opening therethrough coinciding substantially with the die receiving opening, wear-resistant strips secured within said holder adjacent said spring forming a protective surface against which a die may make slidable contact and spacer members secured to the under side of said body portion.

4. A tool-holder within which a stamping die or the like is adapted to be yieldably secured in the stamping position comprising a grip, an elongated body portion having a plurality of die receiving openings extending therethrough from one side to another thereof and a plurality of openings communicating with said die-receiving openings and extending substantially at right angles thereto, yieldable means in each of said

4

last-mentioned openings extending into said die receiving openings for engaging with the exterior walls of dies inserted in the die openings, a removable cover plate on said body portion fitted over the outside end of said second-mentioned openings, a wear-resistant strip fitted in said body portion at the juncture of said openings and forming a partial closure of the second-mentioned openings and limiting the axial and lateral movement of said yieldable means, a shock-resistant plate in locked engagement with the body portion on the side from which a die is normally inserted and having openings therethrough coinciding substantially with the die receiving openings, and spacer members secured to the under side of said body portion.

5. A tool-holder within which a stamping die or the like is adapted to be yieldably secured in the stamping position comprising a grip, an elongated body portion having a plurality of die receiving openings extending therethrough from one side to another and a plurality of other openings communicating therewith from a third side of said body portion, yieldable means in each of said last-mentioned openings which extend therefrom into said die-receiving openings for engaging with the outer surface of dies when inserted in said die-receiving opening, a cover plate on said body portion extending over the outer ends of said second-mentioned openings, a plurality of wear-resistant strips fitted in said body portion at the upper and lower edges where the two sides of said openings come together and forming a partial closure of the second-mentioned openings for confining said yieldable means, a shock resistant plate having locked engagement with said body portion over the portion thereof at the entry end of said die-receiving openings and having openings therethrough coinciding substantially with the die receiving openings, and spacer members secured to the under side of said body portion for exposing the marking end of the die elements.

LEON C. HAUER.
